CLAIM

The ornamental design for a cup holder insert with cell phone retainer, as shown and described.

DESCRIPTION

FIG. 1 is a perspective view of a cup holder insert with cell phone retainer showing my new design;

FIG. 2 is a front view thereof;

FIG. 3 is a rear view thereof;

FIG. 4 is a side view thereof;

FIG. 5 is a top view thereof; and,

FIG. 6 is a bottom view thereof.

Due to the symmetry of the cup holder insert with cell phone retainer design, separate left and right side views are not needed as being redundant.

In the drawings, the broken lines depict environmental subject matter only and form no part of the claimed design.
